His Attorney.

UNITED STATES PATENT OFFICE.

WILHELM PAPE, OF CHARLOTTENBURG, GERMANY, ASSIGNOR TO GENERAL ELECTRIC COMPANY, A CORPORATION OF NEW YORK.

ELASTIC-FLUID TURBINE.

1,194,312.

Specification of Letters Patent.

Patented Aug. 8, 1916.

Application filed July 13, 1915. Serial No. 39,724.

To all whom it may concern:

Be it known that I, WILHELM PAPE, a subject of the German Emperor, residing at Charlottenburg, Germany, have invented 5 certain new and useful Improvements in Elastic-Fluid Turbines, of which the following is a specification.

The present invention relates to elastic fluid turbines, particularly steam turbines, 10 from which elastic fluid is extracted or drawn off from an intermediate stage for industrial purposes.

In the following specification the invention is described in connection with steam turbines, but it will be understood that it is 15 not so limited.

In such turbine installations the extraction conduit is connected to an intermediate stage of the machine and a suitable over- 20 flow valve mechanism is employed between the extraction stage and the next lower stage which is automatically regulated to maintain the pressure in the extraction stage constant. In connection with such

25 turbine installations it is also customary to provide some means for automatically maintaining the pressure in the extraction conduit constant; *i. e.*, maintaining the steam supply, when the turbine is temporarily 30 shut down, as for example when the emergency valve is tripped in case of over-speeding brought about, for instance, by the load being suddenly taken off the turbine. This pressure may be maintained constant in the

35 extraction conduit by admitting live steam directly thereto, or in case other machines are operating in parallel, by extracting more steam from them, or both means may be used. In any event, however, it would be 40 dangerous to have low pressure steam flow from the extraction conduit back through the low pressure end of the turbine at a time when its load was off, as this would cause racing, which, as is well known, may cause

45 dangerous strains or even result in substantial injury to or destruction of some of the parts, and to obviate this danger a suitable non-return valve is ordinarily provided in the extraction conduit. I have found, however, that owing to the fact that the non- 50 return valve is only called into play at long intervals of time, there is possibility of its sticking open or failing to close completely at the desired time, and hence it is a source 55 of more or less danger.

The object of the present invention is to provide an improved arrangement of regulating and controlling mechanism for such an elastic fluid turbine which will operate in case the non-return valve fails to function properly to effectually protect the turbine from the possibility of racing and injury due to such cause. To this end I provide a controlling mechanism which, in case the speed of the turbine rises above a predetermined maximum, will operate to positively close the overflow valve, and thus prevent steam from flowing from the extraction conduit through the low pressure end of the turbine in case of failure of the non-return valve to operate. In addition to this, I may also provide an emergency trip or shut-off valve in the extraction conduit between the non-return valve and the turbine, which valve is automatically closed 70 when a certain maximum speed is reached. It may be operated independently of, or in connection with, the mechanism which operates the overflow valve.

For a consideration of what I believe to 80 be novel and my invention, attention is directed to the accompanying description and the claims appended thereto.

In the accompanying drawing Figure 1 is a more or less diagrammatic view in outline and partly in section of an embodiment 85 of my invention, and Fig. 2 is a sectional view showing one arrangement of one of the automatic valves.

Referring to the drawing, 3 indicates the 90 high pressure end and 4 the low pressure end of an extraction turbine. 5 indicates the steam chest to which live steam flows by way of conduit 6, and 5^a the exhaust conduit which leads to a suitable condenser 95 (not shown). Located in the steam chest is a suitable valve mechanism comprising a series of valve seats 7 upon which the valves 8 rest. The valves 8 have a common operating stem 9 which passes freely down through them 100 and carries a series of collars 10 arranged to successively pick up the valves and lift them from their seats. The stem 9 extends through the top wall of the steam chest and is connected to the piston 11 of a fluid motor. 105

12 indicates the cylinder of the motor, and 13 the usual pilot valve having its stem 14 connected to a floating lever 15. One end of this lever is connected to the spindle of 110

speed governor 16 and the other end is connected to the stem 9, thus forming a usual form of follow-up device to prevent overtravel of the motor.

5 17 indicates an extraction conduit connected with an intermediate stage of the turbine, as here shown, the first stage. In the present instance it is shown as leading to a header 18 from which conduit 19 con-
10 veys steam to a point or points of consump-
tion for industrial purposes.

20 indicates a second conduit leading to the header 18 and may represent an extraction conduit from a second machine operating in parallel with the first. Arranged in
15 conduit 17 is a suitable non-return valve 21 which closes in case steam tends to flow from the header back toward the turbine. In the conduit is also shown an emergency
20 shut-off valve 22 which may be of any suitable type and controlled in any suitable manner to close in case of excess speed. In the present instance it is shown as a butterfly valve. Connected with the conduit 17
25 is a pipe 23 through which live steam may be supplied to the extraction conduit to keep up the pressure therein when the supply of steam from the turbine fails. In this pipe is a valve 24 which is arranged to
30 function automatically for the desired purpose. To this end the valve 24 may be arranged as shown in Fig. 2, wherein a balanced valve is shown having its stem connected to a piston 24^a moving in a cylinder
35 24^b. The valve is biased toward closed position by the pressure exerted on the lower side of the piston 24^a, which is the pressure of the extraction conduit 17. Connected with the valve stem and tending to open the
40 valve is an adjustable weight 24^c. This weight is so adjusted that with normal pressure in the extraction conduit 17 the valve 24 will be held closed. In case, however,
45 this pressure drops slightly, the weight 24^c will be sufficient to overcome the pressure in the lower side of piston 24^a and forces the valve toward open position.

25 indicates a usual type of overflow valve arranged between the extraction stage and
50 the next lower with its stem 26 connected to the piston 27 of a fluid operated motor.

28 indicates the cylinder of the motor and 29 the pilot valve having its stem 30 connected to one end of lever 31 pivoted at 32. The
55 other end of lever 31 is connected to the stem of the pressure-responsive device 33 which may be of any suitable structure and operates in the usual manner to regulate the overflow valve to maintain the pressure in
60 the extraction stage at the desired value. The pilot valve 29 has a sliding sleeve 34 which carries the ports of the pilot valve and to this sleeve is attached one end of a
65 stem 35, the other end being connected to a piston 36 which moves in a cylinder 37

formed as an extension of the pilot valve casing. The pilot valve for the motor made up of piston 36 and cylinder 37 comprises a casing 38 mounted on motor cylinder 12 and valve members 39 having their common stem 70 40 connected to the piston 11.

41 and 42 are pipes connecting pilot valve casing 38 to motor casing 37.

In the present instance I have shown an arrangement in which the emergency valve 75 22 in the extraction conduit is controlled by the same mechanism as controls the overflow valve. To this end the valve 22 is closed by a motor 45 connected to pipes 41 and 42 by pipes 46 and 47. That is, this motor is connected 80 in parallel with the motor made up of piston 36 and cylinder 37 and is controlled by the same pilot valve. It will be understood that this valve device 22 is something in addition to the means for closing the overflow 85 valve and may be used or not as found desirable.

During normal operation the supply of steam to the turbine will be controlled by the speed governor 16 in the usual manner and 90 the overflow valve 25 will be regulated by the pressure-responsive device 33 to maintain the pressure in the extraction stage at the desired value. The sliding sleeve 34 will remain stationary owing to the fact that during 95 normal operation the pilot valve members 39 are not moved sufficiently by the motor piston 11 to uncover the ports. Of course, the emergency shut-off valve 22 (if one is provided) will be open and also the 100 non-return valve 21; the valve 24 will be closed. If for any reason the load on the turbine should fall suddenly or go off the speed governor will operate to shut off the valve mechanism which controls the supply 105 of live steam to the turbine. At the same time, the supply of steam to the extraction conduit will be maintained by the valve 24 automatically opening, or by a machine connected in parallel supplying more steam 110 through conduit 20. If now the non-return valve should stick or fail to close completely permitting steam to pass through the extraction conduit to the turbine tending to cause it to race, then the speed governor 115 which has already operated to close off the supply of live steam will cause the piston 11 of the motor to move down still farther (this being possible since the stem 9 slides freely through the valve member 8), to operate the pilot valve comprising cylinder 38 and valves 39 which in turn admit fluid above the piston 36 causing it to lower sleeve 34, thus admitting fluid above piston 27 to positively seat the overflow valve 25. 120 At the same time, fluid will pass by way of pipe 46 to the motor 45, operating it to close the valve 22.

In accordance with the provisions of the patent statutes, I have described the prin- 130

5 ciple of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. In an elastic fluid turbine having an extraction conduit connected with an intermediate stage, and an overflow valve between such stage and the next lower, the combination of a valve mechanism controlling the supply of elastic fluid to the turbine, 10 a speed governor for regulating said mechanism, a pressure responsive device which regulates the overflow valve independently of the speed governor, and means controlled by said speed governor for positively closing the overflow valve after the governor has 15 closed said valve mechanism in case the speed exceeds a predetermined maximum..
2. In an elastic fluid turbine having an extraction conduit connected with an intermediate stage, and an overflow valve between such stage and the next lower, the combination of a valve mechanism controlling the supply of elastic fluid to the turbine, a speed governor for regulating said mechanism, a 20 motor having a pilot valve for operating the overflow valve, a pressure-responsive device for regulating the pilot valve, a sliding sleeve which carries the ports of the pilot valve, and means regulated by the speed governor for moving the sliding sleeve in a 25 direction to cause the motor to positively close the overflow valve in case the speed exceeds a predetermined maximum.
3. In an elastic fluid turbine having an extraction conduit connected with an intermediate stage, and an overflow valve between such stage and the next lower, the combination of a valve mechanism controlling the supply of elastic fluid to the turbine, 30

said valve mechanism having a stem capable 45 of independent movement after said valve mechanism is closed, a speed governor for controlling the movements of the stem, a pressure-responsive device for controlling the overflow valve, and means which is operated when the stem is moved by the speed governor after the valve mechanism is closed to positively close the overflow valve.

4. In an elastic fluid turbine having an extraction conduit connected with an intermediate stage, and an overflow valve between such stage and the next lower, the combination of a valve mechanism controlling the supply of elastic fluid to the turbine, a speed governor, a non-return valve in the extraction conduit, an emergency shut-off valve in the extraction conduit located between the non-return valve and the turbine, a speed governor which controls the valve mechanism, and means controlled by the governor 60 for positively closing the overflow valve and also closing the emergency shut-off valve when the speed exceeds a predetermined maximum.

5. In an elastic fluid turbine having an extraction conduit connected to an intermediate stage, a non-return valve in said conduit, and an overflow valve between the extraction stage and the next lower, the combination of a valve mechanism controlling the supply of 75 elastic fluid to the turbine, a fluid motor therefor, a speed governor for the motor, a fluid motor for the overflow valve, a pressure-responsive device for controlling it, the pilot valve of said last-named motor having 80 a sliding sleeve which carries its ports, and a fluid motor for moving said sleeve having its pilot valve controlled by the movement of the first-named motor.

In witness whereof, I have hereunto set 85 my hand this 15th day of May, 1915.

WILHELM PAPE.
